ACCOUNTING MACHINE

Arthur R. Colley, Oakwood, Ohio, assignor to The
National Cash Register Company, Dayton,
Ohio, a corporation of Maryland

Original application January 30, 1941, Serial No.
376,670. Divided and this application Decem-
ber 9, 1943, Serial No. 513,556

4 Claims. (Cl. 235—2)

This application is a division of the application of Pascal Spurlino, William M. Carroll, Arthur R. Colley, and Alfred G. Kibler, Serial No. 376,670, filed January 30, 1941, which issued into Patent No. 2,375,594 on May 8, 1945.

The present invention relates to accounting machines and is shown applied to a "commercial posting" or "bank service" machine, and is illustrated as a means for counting checks.

The present invention is embodied in a machine of the general type disclosed in the following United States patents, to which reference may be had for a complete showing and description of standard mechanism not fully disclosed herein: United States Patents No. 1,619,796, No. 1,747,397, and No. 1,761,542, issued, respectively, March 1, 1927, February 18, 1930, and June 3, 1930, to Bernis M. Shipley; Patent No. 2,175,346, issued October 10, 1939, to Maximilian M. Goldberg; Patent No. 2,141,332, issued December 27, 1938, to Charles H. Arnold; and Patent No. 1,693,279, issued November 27, 1928, to Walter J. Kreider. The machine embodying the instant invention as presently constructed is commonly referred to as a "commercial posting" or "bank service" machine and is used by banks and similar institutions for the posting of individual checking accounts.

It is common practice to post each individual checking account daily, provided said individual accounts remain active every day, and this posting includes the picking up of old balances; the subtracting of debits, generally in the nature of checks drawn against said account from said old balance; the addition of credits, generally in the nature of deposits to said account; and the performing of a total-taking operation to arrive at a new balance.

While the machine of this invention is arranged for use by banks in the posting of individual checking accounts, it is not the desire to limit said machine to such use, as, with minor alterations and adjustments, it may be arranged for use in connection with numerous other types of business systems, all coming within the scope of this invention.

The object of the invention is to provide means for counting the number of a certain item recorded during the balancing of one account.

Another object is to supply means to automatically count "one" when the amount of a certain item is recorded, said means also adapted to be manually controlled to count a plurality of items when the total amount of said items is recorded.

With these and incidental objects in view, the

invention includes certain novel features of construction and combinations of parts, the essential elements of which are set forth in appended claims and a preferred form or embodiment of

5 which is hereinafter described with reference to the drawings which accompany and form a part of this specification.

In said drawings:

Fig. 1 is a diagrammatic plan view of the key-board of the machine embodying the instant invention.

Fig. 2 is a sectional view taken just to the right of one of the amount banks, showing the mechanism associated therewith.

15 Fig. 3 is a sectional view taken to the right of the transaction bank, showing the mechanism associated therewith.

Fig. 4 is a detail view of one of the keys in the units check-counting bank and a portion of the mechanism associated therewith.

20 Fig. 5 is a perspective view of the mechanism for controlling the automatic check-counting mechanism.

Fig. 6 is a detail view of one of the keys in the tens check-counting bank and a portion of the mechanism associated therewith.

25 Fig. 7 is a detail view of a control plate operated by the total keys for rendering the automatic check-counting mechanism inoperative during total or sub-total printing operations.

Fig. 8 is a detail view of a control plate associated with the transaction keys for controlling the automatic check-counting mechanism.

30 Fig. 9 is a front view of the No. 1 or balance 35 totalizer line.

GENERAL DESCRIPTION

The machine embodying the instant invention 40 is of the general type disclosed in the Arnold Patent No. 2,141,332, referred to hereinbefore, and is provided with a column-printing mechanism located at the front of the machine for simultaneously recording identical data in one or 45 more columns of an insertable slip or bill during one operating cycle of the printing mechanism. Machines of this character are useful in the preparation of bills or statements by banks, public utility companies, and the like, said bills or statements being provided with a plurality of vertical 50 columns either for the printing of the same data in the several columns, or for the printing of different data in said columns. Likewise, the statements or bills may be provided with two 55 separable portions containing identical data, one

for the customer and one to be retained as a file copy.

In the present case, the specific example chosen to illustrate the system used in connection with the machine of this invention is the preparation, by a banking institution, of statement slips of the individual checking accounts of a plurality of customers of said institution. However, it is not the desire or intention to limit this machine to the banking system outlined above, for, as previously stated, with minor alterations and adjustments, said machine may readily be adapted for use in connection with many business systems.

The main portion of the machine of this invention is of standard construction, and, as this standard mechanism is fully disclosed in the patents referred to at the beginning of this specification, such mechanism will be but briefly treated herein.

The machine chosen to illustrate the present invention is provided with a plurality of rows of amount keys for entering amounts in the various totalizers with which the machine is equipped and for setting up corresponding type wheels to record the amount on record material. The machine also has a row of transaction keys for entering positive and negative items in the various totalizers and a row of symbol-printing keys for printing symbols for identifying the various items. Instead of the conventional total control lever, this machine is equipped with a row of total control keys which control the functions of the machine, including adding, subtracting, reading, and resetting operations. A key release lever, located on the right-hand side of the keyboard, is used for releasing any depressed keys.

The machine embodying this invention is provided with an automatic counting mechanism for counting "one" automatically each time a certain key—in this case the check key—is depressed in an operation. The check-counting wheels are located in the two highest order positions on the balance totalizer line. However, these wheels are not connected with the balance totalizer in any way and automatically count up to 99 checks. A check Correction transaction key is provided for correcting checks or other debit items which have been entered erroneously, and, when this key is depressed, it causes "one" to be subtracted from the check-counting wheels by adding the complementary figure of 99 in said wheels. In addition to the automatic counting of checks, two rows of keys are provided at the left-hand end of the keyboard for use in setting up the number of checks in a bundle when the total amount of these checks is entered as one item during one operation of the machine. Various interlocks are provided for controlling the automatic check-counting mechanism.

The present machine is provided with two totalizer lines (Fig. 2); namely, an upper or No. 1 totalizer line and a back or No. 2 totalizer line. The upper or No. 1 totalizer line supports the balance totalizer, often referred to as a cross-footer, which is used for computing positive and negative amounts to arrive at new balances. The back or No. 2 totalizer line has thereon four totalizers, two of which are add-subtract totalizers, one for keeping a total of the debit or check items and the other for keeping a total of the credit or deposit items. The reason add and subtract totalizers are used for totals of checks and deposits is that, in check correction and

deposit correction operations, it is necessary to subtract in these totalizers in order to secure a correct total.

DETAILED DESCRIPTION

Framework and operating mechanism

The main framework of the machine comprises a left frame 60 (Figs. 2 and 3) and a similar right frame (not shown), which support most of the machine mechanism and which are in turn secured to a machine base 61 and are further supported in relation to each other by various cross frames, rods, and bars. The base plate 61 rests on and is secured to four printer frames, one of which, 64, is shown herein Figs. 2 and 3. The printer frames are secured in fixed relationship to each other by various bars, rods, and shafts, as shown in the parent application. The printer frames are in turn secured to the top surface of a sub-base (not shown), and the mechanism of the machine is enclosed in a suitable case or cabinet 68 (Fig. 2).

Depression of any one of the "operating" keys releases a key lock shaft 69 (Fig. 2) to the action of a spring (not shown), which rocks said shaft a slight distance clockwise to operate the clutch mechanism which connects the operating motor to a main shaft 70 (Figs. 2 and 3) journaled in the main frame 60, and simultaneously operates the switch mechanism which closes the circuit to the operating motor, causing said motor to function. After the machine has performed the proper number of cycles to complete the type of operation being executed, the key lock shaft 69 is returned counter-clockwise to disengage the clutch mechanism and to simultaneously open the switch to the electric motor. When the machine is operated manually, the "operating" keys are used for releasing the machine in exactly the same manner as when said machine is operated electrically.

Keyboard

Referring to Fig. 1, which is a diagrammatic showing of the keyboard, it will be seen that there are nine rows of amount keys 71 and two rows of check-counting keys 52 and 72, which are similar in many respects to the amount keys 71 but have their own counting wheels on the No. 1 or upper totalizer line for counting the number of checks listed in posting an account.

The present machine is provided with a total control plate for controlling the engaging and disengaging movements of the two totalizer lines in adding, subtracting, total-printing, and subtotal-printing operations. The positioning of the total control plate is controlled by a plurality of total control keys (Fig. 1) numbered 74 to 78 inclusive and located near the right-hand side of the keyboard. The total control keys 74, 75, and 78 are motorized or operating keys and are used to initiate operation of the machine.

The present machine is provided with two lines of totalizers which are selected for engagement with the amount actuators by the use of keys in a transaction row (Figs. 1 and 3) located adjacent the total control keys and numbered 79 to 84 inclusive, all of which are operating keys. In addition to the operating keys 79 to 84, the transaction row also contains a Space Ledger key 85 for spacing the combined statement and ledger sheet table; an Overdraft key 86, which is used to unlock the New Balance key 74 when the balance totalizer contains an overdraft; and a Re-

lease Lock-Proof key 87, which is used to unlock the Overdraft Pick-Up key 79 and the Balance Pick-Up key 84 when there is an amount in the balance totalizer. After an old balance is picked up and entered in the machine by the use of either the Overdraft Pick-Up Key 79 or the Balance Pick-Up key 84, these keys are then locked against depression until a new balance is taken, thus insuring that the old balance is not picked up more than once. The Release Lock-Proof Key 87 is used to unlock these keys in case it is desired to use the keys 79 and 84 more than once.

Normally the Overdraft Pick-Up key 79 and the Balance Pick-Up key 84 do not print upon the statement sheet; however, when it is desired to have the old balance recorded, a Balance Forward key 88, located in the total row, is depressed in conjunction with these keys and causes the amount of the old balance to be printed on the "Balance Forward" line of the statement sheet. A Release key 89 is provided for releasing the Balance Forward key, which is not released automatically at the end of machine operations. The Space Ledger key 85, like the transaction keys 79 to 84 inclusive, is an operating key.

Located to the left of the transaction keys is a symbol row containing ten keys for printing identifying symbols adjacent items listed under the influence of the transaction keys. The symbol keys 90 are normally staydown keys; however, a release key 91, located at the top of this row of keys, is provided for releasing the symbol keys when desired. The NC symbol key is depressed in conjunction with the Check key 82 when it is desired not to have the debit item being posted counted by the automatic check-counting mechanism. In other words, the NC symbol key, which signifies "non-count," disables the automatic check-counting mechanism. The NC key, in addition to disabling the automatic check-counting mechanism, also causes the symbol NC to be printed opposite the debit item or check which was not counted.

The monthly bookkeeping or service charge is deducted from the customer's account by setting up the amount on the amount keys 71 and using the Check key 82. When the service charge is posted, the SC symbol key 90 is depressed in conjunction with the Check key 82 to cause the symbol for service charge ("SC") to be printed opposite the amount of the service charge, and the depression of the SC key also disables the automatic check-counting mechanism, so that the service charge item will not be counted.

All of the symbol keys 90, with the exception of the NC and the SC keys, are simply printing keys and cause identifying symbols to be printed opposite the corresponding items. For example, the IN key is an Interest key and causes the symbol IN to be printed opposite the amount of an interest item. The LS or List symbol key is used when it is desired to list the total amount of a bunch of checks in one check operation, and this type of operation is identified as such by the symbol LS printed opposite the amount. When the total amount of a bunch of checks is listed in this manner, the number of checks in the bunch is set up on the check-counting keys 52 and 72, thus causing the total number of checks to be entered in the check-counting wheels. The use of the check-counting keys 52 and 72 to list the number of checks in a bunch or bundle renders the automatic check-counting mechanism inoperative during such listing.

The position occupied by the symbol Release key 91 (Fig. 1) is also an automatic position for automatically printing the symbol EC for Error Correction and is rendered effective by depression of either the Deposit Correction key 86 or the Check Correction key 83.

A Key Release Lever 92 (Fig. 1), located at the extreme right-hand side of the keyboard, is provided for releasing any of the keys with the exception of the stay-down keys, which include the Symbol keys 90 and the Balance Forward key 88.

The manner in which the total control keys 14 to 78 inclusive and the total control plate 15 control the engaging and disengaging movements of the two totalizer lines is fully explained in the Shipley patents referred to previously and in the United States Patent No. 2,262,256, issued to Shipley et al. on November 11, 1941, to which reference may be had for a more detailed description of this mechanism.

Amount banks and amount differentials

The nine banks of amount keys and their associated differential mechanisms are alike in every respect and are similar in construction to those shown in the patents to Shipley and Goldberg referred to hereinbefore. Inasmuch as the amount banks are alike, it is believed that a description of one of said banks and the differential mechanism associated therewith will be sufficient.

Fig. 2 is a transverse sectional view of the machine taken just to the right of one of the amount banks, showing said bank and its associated differential mechanism, which will be considered as representative of all the amount banks.

The amount keys 71 are mounted in a key bank framework 93 supported by rods 94 and 95 extending between the main frames 60 of the machine. The depression of any one of the amount keys 71 rocks a zero stop pawl 96, for this particular denomination, counter-clockwise out of the path of a reset spider 97 free on a hub of an amount differential actuator 98 rotatably supported on a bushing 99 extending between two similar support plates 100 (only one shown here), said plates in turn supported by rods 101 and 102 extending between the main frames 60. There is a pair of supporting plates 100 for each amount differential mechanism, and a tie rod 103 extends through holes in the center of the bushings 99 to secure all of the amount differentials in a compact unit.

A slot in the forward end of the spider 97 engages a stud 104 in a forward extension of a bell crank 105 pivoted on an extension of the actuator 98. The bell crank 105 and a companion crank 106, likewise pivoted on the extension 60 of the actuator 98, together support a differential latch 107 for horizontal shifting movement. A spring 108 urges the cranks 105 and 106 and the latch 107 rearwardly to normally hold a foot-shaped projection 109 of said latch in engagement with a shoulder 110 on a differential driving segment 111 rotatably supported on the hub of the actuator 98. A link 112 pivotally connects the driving segment 111 to a cam lever 113 pivoted on a stud 114 in the left-hand one of the plates 100, and said lever 113 carries rollers 115 and 116, which cooperate, respectively, with the peripheries of companion plate cams 117 and 118 secured on the main shaft 10. Depression of any one of the amount keys 71 moves the lower end of the stem thereof into the path of a

rounded surface 119 on an extension of one arm of the bell crank 105.

In adding operations, the main shaft 70 and the cams 117 and 118 make one clockwise revolution, causing the lever 113 to rock the driving segment 111 first clockwise and then back to normal position. Clockwise movement of the segment 111 causes the shoulder 110 thereon, in cooperation with the extension 109 of the latch 107, to carry said latch and the amount actuator 98 clockwise in unison therewith until the rounded surface 119 contacts the stem of the depressed amount key 71. This rocks the bell crank 105 and its companion crank 106 counterclockwise to disengage the projection 109 from the shoulder 110 to interrupt the clockwise movement of the actuator 98 and to position said actuator in proportion to the depressed amount key 71. Disengaging movement of the latch 107 moves a rounded extension 120 thereof into engagement with the corresponding one of a series of locating notches 121 in a plate 122 secured between the rod 101 and an upward extension of the left-hand support plate 100.

After the latch 107 is disengaged from the shoulder 110, an arcuate surface 125 on the segment 111 moves opposite the projection 109 to retain said latch in set position.

When the lever 113 reaches the terminus of its clockwise movement, a roller 126 carried thereby engages an arcuate surface 127 on a beam 128 pivoted on a stud 129 in the actuator 98 and forces a concave surface on the upper edge of said beam into contact with the hub of the actuator 98 to position said beam in proportion to the depressed amount key.

The beam 128 (Fig. 2) has therein a slot 130, which engages a stud 131 in a link 132, the upper end of which link is pivoted to a segment 134 mounted on one of a series of nested tubes 135 supported by a shaft 136 journaled in the main frame 60. The lower end of the link 132 is pivotally connected to a segment 137 free on a shaft 138 journaled in the frame 60. The segment 137 carries a stud 139, which engages a camming slot in a zero elimination cam plate 140 pivotally mounted on a stud 141 in a segmental gear 142 free on a shaft 143 journaled in the main frames 60.

The teeth of the segmental gear 142 mesh with the external teeth of an external-internal ring gear 144 (Fig. 2) having internal teeth, which, in cooperation with the periphery of a disk 145 fixed on a shaft 146 supported by brackets 147 (Fig. 3) secured to a cross bar 148 and the main framework of the machine, form a rotatable support for said gear 144. The bar 148 (Fig. 3) is secured to the main frames 60 of the machine. The internal teeth of the ring gear 144 (Fig. 2) mesh with a pinion 149 rotatably supported in a boring in the disk 145 and secured to a square shaft 150. The pinion 149 and the square shaft in turn drive pinions similar to the pinion 149, which drive connections to type carriers, as shown in the parent case.

The external-internal gear method of driving the type wheels of column-printing accounting machines is fully explained in United States Patent No. 2,141,332, issued to Charles H. Arnold, and embodies an application of the well-known principle of type wheel driving mechanism disclosed in United States Patent No. 1,693,279, issued to Walter J. Kreider.

The plate 140 (Fig. 2) carries a stud 155, which is engaged by a slot in the end of a zero elim-

ination operating slide 156 having parallel slots which engage, respectively, a shaft 157 journaled in brackets 158 secured to the base 61, and a rod 159 supported by arms 160 (only one shown here) secured to the shaft 157. A spring 161, tensioned between the segment 137 and the plate 140, normally maintains the lower end of the cam slot in said plate 140 in engagement with the stud 155, as shown here.

Inasmuch as the zero elimination mechanism shown here is similar to and functions precisely like the zero elimination mechanism disclosed in United States Patent No. 2,141,333, issued December 27, 1938, to Charles H. Arnold, it is believed that a brief description of this mechanism as shown in Fig. 2 will be sufficient.

The zero elimination slide 156 carries a roller 162, which cooperates with an arcuate surface 163 on a slide-operating arm 164 free on a shaft 165 journaled in the brackets 158. The arm 164 is connected by a hub 166 free on the shaft 165 to a companion arm 167, which cooperates with a stud 168 in the arm 164 for the next lower denomination. Likewise, the arm 164 for the denomination being described carries a stud 168, which cooperates with the arm 167 for the next higher denomination, and so on. The stud 168 in the arm 164 for the highest denomination cooperates with an arm similar to the arm 167, which is secured to the shaft 165, and said shaft is rocked first clockwise near the beginning of machine operations and back to normal position in the manner shown in Fig. 5 of the Arnold patent referred to above. Clockwise movement of the shaft 165 and the arm 167 for the highest denomination is transmitted through the stud 168 to the arm 164 for said highest denomination, and on down the line through all the denominations to rock the arm 164 shown here first clockwise to shift the slide 156 rearwardly to disengage the slot in said slide from the stud 155 in the cam 140.

Assuming, for example, that a key has been depressed in the amount bank shown in Fig. 2, after the slide 156 therefor has been shifted rearwardly out of engagement with the stud 155 and after the actuator 98 has been positioned under influence of the depressed key 71, the roller 126 engages the arcuate surface 127 to position the beam 128, the link 132, and the segments 134 and 137 in proportion to said depressed amount key. Prior to the positioning of the segment 134 as explained above, an aliner 169 (Fig. 2) secured on the shaft 170 journaled in the main frame 60 is rocked clockwise out of engagement with teeth 171 in the segment 134, and, after said segment is positioned under the influence of the beam 128, said aliner 169 is engaged with the teeth 171 of the segment 134 to secure the segments 134 and 137 against displacement.

Positioning of the segment 137 moves an arcuate surface 172 thereon into the path of a roller 173 carried by the arm 164 for this particular denomination. Consequently, return movement forwardly of the slide 156 under the influence of a spring 174 is obstructed, and said slide is retained in its rearward position. The stud 168 in the arm 164 for the denomination shown in Fig. 2 obstructs return movement counter-clockwise of the arm 164 for the next lower denomination, and so on down the line, to hold the slides 156 for all lower denominations in rearward position to retain the slots in said slides out of engagement with the studs 155, so that no movement will be imparted to the cam plate 140.

when the shaft 157 and the arms 160 are rocked counter-clockwise and back to normal position after the segments 137 have been positioned under the influence of the depressed amount keys, as explained above.

When no key 71 is depressed in the amount bank shown in Fig. 2 or in any of the higher order amount banks, the segment 137 is positioned at zero, as shown here, in which position a clearance portion of said segment is opposite the roller 173. This permits return movement forwardly of the arm 164 and the slide 156, under the influence of the spring 174, to cause the notch in the end of said slide to reengage the stud 155. After the notch in the slide has reengaged the stud 155, counter-clockwise movement is imparted to the shaft 157, the arms 160, and the slide 156 by mechanism similar to that shown in Fig. 4 of the Arnold Patent No. 2,141,333, referred to above. Counter-clockwise movement of the slide 156 rocks the zero elimination cam plate 140 clockwise, causing the cam slot therein, in cooperation with the stud 138, which is held stationary at this time, to rock the segment 142 counter-clockwise against the action of the spring 161 to move the ring gear 144 clockwise from zero position, as shown here, to one position beyond zero, which in this case is a blank or non-printing position. Obviously, zero printing will be eliminated in a like manner in all higher denominations. In other words, the zero elimination mechanism functions when a key 71 is depressed in row five of the amount keys (Fig. 1) to cause the zeros to print in the four lower denominations and to eliminate the printing of zeros in the four higher denominations.

After the amount actuator 98 (Fig. 2) has been positioned under the influence of the depressed amount key 71, as explained above, the wheels of the selected totalizer are engaged with the corresponding one of two sets of teeth 175 and 176 thereon, after which return movement of the cam lever 113 and the segment 111 causes the arcuate surface 125 on said segment to move beyond the sole of the projection 109 on the latch 107 to permit said latch, under the influence of the spring 108, to drop behind the shoulder 110 to disengage the rounded nose 120 of said latch from the notch 121 in the plate 122. At the same time, an enlarged surface on the segment 111 engages a stud 179 carried by the actuator 98 and returns said actuator counter-clockwise in unison with said segment to zero position. This return movement counter-clockwise of the actuator 98 rotates the wheels of the engaged totalizer or totalizers in proportion to the value of the depressed amount key 71 to add or subtract in said totalizer or totalizers the amount represented by the depressed amount key 71.

If no amount key 71 is depressed, the zero stop pawl 96 remains in the path of the spider 97 and, upon initial movement of said spider and the actuator 98, engages an extension of said spider and breaks the latch 107 in zero position, after which the roller 126, in cooperation with the beam 128, positions the segments 134 and 137 and associated mechanism in proportion thereto to position the type wheels for this particular amount bank in zero position.

At the end of any type of operation, the actuator 98 (Fig. 2) is always returned to home position, as shown here; however, the link 132 and the segments 134 and 137 and the printing mechanism controlled thereby remain in set position at the end of the machine operation and are moved

directly from this set position to their new position in the succeeding machine operation. The usual transfer mechanism is provided for transferring tens digits from lower to higher denominations in adding and subtracting operations.

Totalizers

As explained previously, the machine embodying this invention has two lines of totalizers, including an upper or No. 1 totalizer line and a back or No. 2 totalizer line. The No. 1 totalizer is a balance totalizer, often referred to as a cross-footer, and comprises denominational sets of plus wheels 180 (Fig. 2) and denominational sets of minus wheels 181, said plus and minus wheels of each denominational order being reversely geared together, so that when one wheel is turned in one direction the other turns in the opposite direction and vice versa. The balance totalizer is supported in a shiftable framework 183 (Fig. 2) in turn supported between the main frames 60. The shiftable framework 183 for the balance totalizer includes a shaft 184 (Fig. 2) having mounted on opposite ends thereof rollers which engage similar guide slots in two shifting cam plates, as shown in the above-named patents and in the parent case, secured, respectively, to the right and left main frames 60.

30 The mechanism for engaging and disengaging the totalizers with and from the actuators 175 and 176 is well known in the art, and, for a detailed description thereof, reference may be had to the parent case and to the patents referred to above.

35 The No. 2 or back totalizer line (Fig. 2) has thereon two add-subtract totalizers, one for the storing of checks and the other for the storing of deposits, the add-subtract feature being necessary in each case for the check and deposit correction features. The add-subtract totalizer for the storing of checks comprises adding wheels and subtracting wheels 218, which are geared together for reverse movement in exactly the same manner as the No. 1 or balance totalizer wheels, explained above. The deposit totalizer comprises adding wheels 219 and subtracting wheels, which are likewise geared together for reverse movement. In addition to the two adding and subtracting totalizers, the No. 2 totalizer line includes a set of adding wheels (not shown) for the storing of total new balances plus and a set of adding wheels (not shown) for the storing of total new balances minus. For a disclosure of these storage totalizers, reference may be had to the parent case.

40 In new balance operations, if the balance totalizer contains a plus amount, the plus side of said balance totalizer will be reset and the amount thereon will be simultaneously transferred to the adding wheels, and if said balance totalizer contains a negative amount, the minus wheels 181 thereof will be reset and the amount thereon will be simultaneously transferred to the subtract wheels on the No. 2 totalizer line. The No. 2 totalizer line is mounted in a shiftable framework 223 (Fig. 2) similar in every respect to the framework 183 for the balance totalizer, and this framework includes a shaft 224 similar to the shaft 184 45 for the balance totalizer. Mounted on each end of the shaft 224 are rollers (not shown here), which cooperate with guide slots in totalizer engaging cam plates mounted on the inside of the main frames 60, as shown in Fig. 16 of the parent case.

Transaction keys and differential mechanism associated therewith

All of the transaction keys, with the exception of the Overdraft key 86 (Fig. 1) and the Release Lock Proof key 87, control the positioning of the transaction differential mechanism shown in Fig. 3. However, only the Deposit key 81, the Deposit Correction key 80, the Check key 82, and the Check Correction key 83 are effective in check-posting operations to select their corresponding sides of the two add-subtract totalizers on the No. 2 totalizer line. The two adding totalizers on the No. 2 totalizer line for storing the total new balances plus and minus are not engaged with the amount actuators in check-posting operations, but are only engaged therewith in new balance operations to store the amount of the new balance. The transaction differential mechanism controlled by the transaction keys, in addition to selecting the totalizers on the No. 2 line corresponding to said keys and the proper side of the balance totalizer for engagement with the amount actuators, also controls the positioning of type wheels for recording characters representative of the type of operation being performed adjacent the amount recorded.

Depression of any one of the transaction keys, with the exception of the keys 86 and 87 (Fig. 3), rocks a zero stop pawl 271 out of the path of the forward end of a spider 272, rotatably supported on a hub 273 on a transaction differential arm 274, said hub 273 in turn being rotatably supported by a stud 275 extending between two identical support plates 276 (only one shown here), mounted on the rods 101 and 102.

The spider 272 has in the forward end thereof a slot, through which extends a stud 277 in a latch-operating arm 278 pivotally mounted on the differential arm 274, and which, in cooperation with a companion arm 279 also pivoted on the arm 274, supports a transaction differential latch 280 for shifting movement. The latch 280 has a foot-shaped extension 281, normally maintained in engagement with a shoulder on a transaction differential operating segment 282 free on the stud 275 by a spring. The segment 282 is connected by a link 283 to a cam lever 284 free on a stud 285 supported by the plate 276. The lever 284 carries rollers 286 and 287, which cooperate, respectively, with the peripheries of companion plate cams 288 and 289 secured on the main shaft 70.

Depression of any one of the transaction keys, with the exception of the keys 86 and 87, moves the lower end of said key into the path of a rounded extension 292 of the latch arm 278 at the same time the zero stop pawl 271 is moved out of the path of the spider 272. Operation of the machine causes the cams 288 and 289 to rock the lever 284 and the differential operating segment 282 first in a clockwise direction. The shoulder on the segment 282, in cooperation with the extension 281, carries the latch 280 clockwise in unison therewith until the rounded surface 292 engages the stem of the depressed key to rock the arm 278 counter-clockwise to disengage said extension 281 from the shoulder of the segment 282 and to engage a rounded extension 293 on the forward end of said latch 280 with a corresponding notch 294 in an alining plate 295 supported by the rod 101 and the plates 276. This positions the differential arm 274 in proportion to the depressed transaction key. Continued clockwise movement of the segment 282 causes

an arcuate surface 296 thereon, in cooperation with the sole of the foot-shaped extension 281, to lock latch 280 in set position.

When the lever 284 (Fig. 3) nears the terminus of its initial movement clockwise, a roller 297 carried thereby engages a rounded surface 298 on a differential beam 299 pivotally mounted on the arm 274 and forces an arcuate surface on the upper edge of said beam into contact with an undercut portion of the hub 273 to position said beam in proportion to the depressed transaction key. The beam 299 is bifurcated to embrace a stud 301 in a link 302, the upper end of which is pivotally connected to a segment 303 secured to one of the tubes 135 on the shaft 136 and the lower end of said link is pivotally connected to a segment 304 free on the shaft 138 and connected by a link 305 to a gear sector 306 secured on the shaft 143. The gear sector 306 meshes with the external teeth of an external-internal gear 307 rotatably mounted on a disk in turn supported by the shaft 146, and said gear 307 has secured thereto a ring gear 308, which meshes with a pinion 309 secured on a shaft 310 journaled in the brackets 147. Other pinions, secured on the shaft 310, drive other internal-external gears similar to the gear 307, which position transaction type wheels located in the different columnar positions of the record material, so that a character indicative of the transaction being performed will be recorded on said record material. Also secured on the shaft 143 (Fig. 3) is a gear sector 311, which meshes with gear 312 free on a stud 313 secured in the base plate 61. The gear 312 meshes with a gear 314 secured on a shaft 315 journaled in the printer framework, said shaft 315 in turn positioning selecting disks which control the operation of the printing hammers and the movement of the combined statement and ledger slip table. The selecting disk mechanism is fully described in the parent case.

When the Check key 82 (Figs. 1 and 3) is used in check-posting operations, the depression of this key causes the cams (not shown) to select the plus wheels of the No. 2 check totalizer on the No. 2 line for the accumulation of the total amounts of checks.

When it is desired to make a correction in a check entry, the Check Correction key 83 (Fig. 1) is used, and this causes the selecting cams to select the plus side of the No. 2 check totalizer so that the amount of the check correction, which is a credit, will be added in the No. 2 check totalizer.

Check-counting mechanism

A units bank and a tens bank of keys 72 and 52, respectively, located at the extreme left of the keyboard (Fig. 1) and similar in many respects to the amount banks 71 but disconnected therefrom, are provided for the automatic and the manual counting of checks. The automatic counting of checks is controlled by the Check key 82, and the depression of this key controls the zero stop pawl for the units check-counting bank, which zero stop pawl, in addition to the usual zero stop, also has a stop located in the "1" position of the units bank 72. Depression of the Check key 82 brings this second stop into the path of the differential spider for the units check-counting bank and causes "1" to be added in the check-counting wheels 1180 (Fig. 9), which wheels have the same formation as wheels 180 (Fig. 2).

The Check Correction key 83, which is used to

withdraw or cancel a check erroneously posted, also exercises control over the automatic check-counting banks 72 and 52 and causes "1" to be automatically subtracted from the check-counting wheels to compensate for the withdrawal or cancellation of a check. This subtraction of "1" in the check-counting wheels is effected by adding the complement "99" therein, and depression of the Check Correction key 83 releases the zero stop pawls for the units and the tens check-counting banks to permit the differential mechanisms 1175 (Fig. 9) for said banks to travel full distance to ninth positions to effect the subtraction.

Often it is the practice to have all the checks of a certain class or designation assembled in a bundle, and the total amount of each bundle of checks is set up on the amount keys and entered as a single item by using the Check key 82. In this case, the keys 72 and 52 of the two check-counting banks are used to set up the total number of checks in each bundle, and the use of these check-counting keys disables the automatic check-counting mechanism and causes the total number of checks in the bundle to be entered in the check-counting wheels. The check-counting mechanism will now be described in detail.

The banks of check-counting keys 72 and 52 (Fig. 1) are similar in construction to the amount banks 71 (Fig. 2), and each has a differential mechanism including a spider 778 (Fig. 4) for the units keys 72 and a spider 779 (Fig. 6) for the tens keys 52, which are similar to and function in exactly the same manner as the spider 97 for the amount bank shown in Fig. 2. Each spider controls a differential rack 1175 (Fig. 9) like the rack 175 in the amount bank differentials. The spider 778 for the units check-counting bank has a stud 780 with a flat surface thereon, which cooperates with a zero stop surface 781 and a surface 782 corresponding to the "1" position of the units differential mechanism on a zero stop pawl 783 free on a shaft 784 journaled in the machine frame-work. A torsion spring 785, which encircles the shaft 784 and opposite ends of which engage a stud 786 in the stop pawl 783 and a bushing on the rod 101, urges said stop pawls clockwise to normally maintain a tail 787 thereon in contact with the bushing on said rod 101.

The differential spider 779 for the tens check-counting keys 52 (Fig. 6) carries a stud 788 with a flat surface, which cooperates with a zero stop surface 789 on a zero stop pawl 790 free on the shaft 784 and urged clockwise by a torsion spring 791, which encircles the shaft 784, opposite ends of said spring engaging, respectively, a stud 792 in the pawl 790 and the bushing on the rod 101 to normally maintain a tail 793 on said pawl 790 in contact with the bushing on the rod 101. The stud 786 (Fig. 4) carried by the zero stop pawl 783 for the units check-counting bank overlies and cooperates with a lever 795 secured in fixed relationship to a finger 796 by a hub 797 free on the rod 101. The finger 796 (Fig. 4) cooperates with a stud 798 in an upward extension of an arm 799 free on a stud 800 in the key bank framework. The arm 799 has an extending finger 801, which cooperates with a rod 802 supported by a plurality of cranks 803 secured on the zero pawl throwout shaft 204 (see also Fig. 2).

Mechanism similar to that just described for the units check-counting keys is also provided for the tens check-counting keys 52 (Fig. 6). The stud 792 in the zero stop pawl 790 overlies and cooperates with an arm 804 connected by a hub

805 free on the rod 101 to a finger 806, which cooperates with a stud 807 in an upper extension of an arm 808 free on a stud 809 in the tens key frame. An extending finger 810 of the arm 808 cooperates with the rod 802 in the same manner as the finger 801 for the arm 799 (Fig. 4). The studs 798 and 807 (Figs. 4 and 6) in the arms 799 and 808 also cooperate with similar camming surfaces on corresponding levers 811 and 812 pivoted, respectively, on studs 813 and 814, secured, respectively, in the units and tens key frames. Loosely connected to the lever 811 is a lever-operating bar 815, the upper end of which is linked in a similar manner to the key frame, so that said bar may be shifted. The bar 815 has thereon a plurality of camming surfaces, which cooperate, respectively, with studs 818 in each of the units keys 72.

Depression of one of the units keys 72 causes the stud 818, in cooperation with the camming surface 817, to shift the bar 815 downwardly to rock the lever 811 clockwise. Clockwise movement of the lever 811 causes the camming surface thereon, in cooperation with the stud 798, to rock the finger 796, the hub 797, and the lever 795 counter-clockwise. Counterclockwise movement of the lever 795 is transmitted through the stud 786 to the zero stop pawl 783 to rock said pawl to the second position shown in dot-and-dash lines, to move both the "0" surface 781 and the "1" surface 782 out of the path of the stud 780, so that the spider 778 and the associated differential mechanism will be positioned under the influence of the depressed key 72.

The lever 812 for the tens check-counting bank 52 is loosely connected to the lower end of the control bar 816, similar in every respect to the control bar 815 and having thereon a plurality of camming surfaces 819, which cooperate with studs 820 in each of the tens check keys 52. Depression of any one of the keys 52 rocks the lever 812, which in turn rocks the zero stop pawl 790 for the tens bank counterclockwise against the action of the spring 791 to the position shown in dot-and-dash lines in Fig. 6 to move the zero stop surface 789 of said pawl out of the path of the stud 788, so that the spider 779 and its associated differential mechanism will be positioned under the influence of the depressed tens check key 52.

In total and sub-total printing operations, the shaft 204 (Fig. 4) is rocked clockwise in the manner well known in the art and disclosed in the parent application, which movement is imparted to the cranks 803 and the rod 802, causing said rod to engage the fingers 801 and 810 of the arms 808 and 799 (Figs. 4 and 5) to rock said arms counter-clockwise. Counterclockwise movement of the arms 799 and 808, by means of the studs 798 and 807, rocks the fingers 796 and 806 and the levers 795 and 804 counter-clockwise in unison therewith. Counter-clockwise movement of the levers 795 and 804 is transmitted through the studs 786 and 792 to the respective zero stop pawls 783 and 790 to rock said pawls to ineffective positions as explained above, so that the spiders 778 and 779 are free to be positioned by the check-counting wheels, so that the total number of checks may be recorded.

The lever 795 (Fig. 4) for the units check-counting keys has an L-shaped slot 821, through which extends a stud 822, said stud also adapted to cooperate with a projection 823 on the zero stop pawl 783. The stud 822 (Figs. 4 and 5) is secured in a crank 824 secured on the shaft 204.

The lever 804 (Figs. 5 and 6) has an L-shaped slot 825, through which extends a stud 826, which also cooperates with a projection 827 on the zero stop pawl 790 for the tens check keys 52, and said stud 826 is secured in a crank 828 in turn secured on the shaft 784. The shaft 784 extends the full length of the machine and has secured near the right-hand end thereof a crank 829 connected by a link 830 to a control segment 831 for the transaction keys, and said segment is rotatably supported on a bushing 832 similar to and in axial alignment with the bushing 99 (Fig. 2) for the amount bank shown here. A spring 833 urges the segment 831 clockwise to maintain a camming surface 834 thereon (Figs. 5 and 8) in contact with a stud 835 in one arm of a yoke 836 free on a rod 837 supported by the key bank support plates. The yoke 836 is connected by a link 838 to a crank 839 secured to the key lock shaft 69.

Clockwise movement of the key lock shaft 69 (Fig. 8) when the machine is released for operation, as explained in connection with Fig. 2, through the link 838, rocks the yoke 836 counter-clockwise to move the stud 835 away from the raised portion of the cam surface 834 to permit the spring 833 to yieldingly urge the segment 831 in a clockwise direction. Each of the transaction keys 79, 80, 85, 81, and 87 has therein a stud (Figs. 1 and 3), which, when any one of said keys is depressed, is adapted to move into a corresponding notch 841 in the peripheral surface of the segment 831 to obstruct clockwise movement of said segment by the spring 833 when the key lock shaft 69 is rocked clockwise upon release of the machine for operation.

The transaction key 84 has therein a stud, which moves into the path of a shoulder 842 on the right-hand end of the peripheral portion of the segment 831 to obstruct clockwise movement of said segment 831. Consequently, when any one of the keys just named is depressed, the segment 831 will be rendered inoperative. The Check key 82 has therein a stud adapted to cooperate with a notch 843 in the peripheral surface of the segment 831, said notch 843 being substantially larger than the notches 841, thus providing enough clearance between the left-hand or lower wall of said notch and the stud in the Check key 82 to permit partial movement of the segment 831 under the influence of the spring 833 when the key lock shaft 69 is rocked at the beginning of machine operation. This partial clockwise movement of the segment 831 through the link 830 rocks the crank 829, the shaft 784 (Figs. 4, 5, 6, and 8), the crank 824, and the stud 822 counter-clockwise a sufficient distance to cause said stud 822, in cooperation with the extension 823 of the zero stop pawl 783, to rock said pawl counter-clockwise against the action of the spring 785 to move the "0" stop surface 781 thereon out of the path of the stud 780 and to move the "1" stop surface 782 into the path of said stud, so that, upon machine operations, when the Check key 82 is depressed, the differential mechanism for the units check-counting keys 72 and including the spider 718 will be moved to "1" position under the influence of the surface 782 instead of being stopped in zero position. This permits "1" to be counted automatically in the check-counting wheels.

A transfer mechanism between the units and the tens counting wheels effects the transfer of the tens digit to the tens accounting wheel when the units wheel passes through zero. The check-counting wheels are mounted on the No. 1 or

balance totalizer line (Figs. 2 and 9), and, as the balance totalizer is an add-subtract totalizer and is adapted to be shifted laterally to bring either the plus side or the minus side thereof into engaging relationship with the amount actuators, it is necessary to provide two wheels 1180 in each order of the check-counting banks to take care of this condition. The two wheels in each order of the check-counting banks are not geared together for reverse rotation, as are the wheels of the balance totalizer, but instead are secured in fixed relationship to each other by a sleeve 1182, and in effect function the same as one adding wheel. This makes it possible to add checks in the check-counting wheels when the balance totalizer is in subtract position under the influence of the Check key 82 and also makes it possible to take a sub-total or a total of the check-counting wheels when either the plus side or the minus side of the balance totalizer is sub-totalized or totaled.

When the shaft 784 is moved a partial distance by depression of the Check key 82, as explained above, the crank 828 (Figs. 5 and 6) and the stud 826 for the tens check-counting keys 52 are moved in unison therewith. However, it will be noted, by referring to Fig. 6, that sufficient clearance is provided between said stud 826 and the extension 827 on the zero stop pawl 790 for the tens keys and that no movement is imparted to said zero stop pawl 790, and, as a result, the stop surface 789 remains in the path of the stud 788 and positions the differential mechanism for the tens check-counting bank at zero.

35 The Check Correction key 83, as previously explained, is used for correcting a check or debit item which was erroneously entered in a previous operation, and, as this previously-entered check, which is being cancelled in the present operation, was automatically counted by the check-counting mechanism, it is necessary to subtract "1" from the check-counting wheels when a Check Correction operation is performed.

45 By referring to Fig. 5, it will be noted that the Check Correction key 83 has no stud, as have the other transaction keys, and no notch is provided therefor in the periphery of the segment 831. Consequently, depression of the Check Correction key permits full clockwise movement of the segment 831 upon release of the machine for operation, and this full movement is imparted to the shaft 784, the crank 824, and the stud 822 (Figs. 4, 5, and 6) to rock the zero stop pawl 783 for the units check-counting keys 72 full distance to move both surfaces 781 and 782 out of the path of the stud 780. Full movement of the shaft 784, the crank 828, and the stud 826 causes said stud 826, in cooperation with the extension 827, to move the zero stop pawl 790 full distance counter-clockwise to move the zero stop surface 789 thereon out of the path of the stud 788. This frees the differential mechanism for both the units and the tens check-counting banks for full movement to the "9" position to cause the complementary figure "99" to be added in the check-counting wheels, which in effect is the same as subtracting "1" from said wheels.

At times, the Check key 82 (Fig. 1) is used in connection with the amount keys 71 to post items other than checks, and in this case it is desirable to render the automatic check-counting mechanism inoperative. One such debit item, and probably the most commonly used in connection with checking accounts, is the "service charge" for handling the depositors' checking accounts, and

when this item is posted, the automatic check-counting mechanism is disabled by depression of the "SC" symbol key 90, which is always used to designate service charge items. At times, it is desirable not to have the automatic check-counting mechanism function in connection with the posting of checks or other debit items, and depression of the "NC" symbol key 90 disables the automatic check-counting mechanism, so that these items will not be counted.

Secured on the shaft 784 (Fig. 5) is a crank 844 connected by a link 845 to a control segment 846 for the symbol keys 90, said segment being pivoted on the bushing 832 adjacent the control segment 831. A spring 847 urges the segment 846 clockwise to maintain a camming surface 848 on an extension thereof in engagement with the stud 835 in exactly the same manner as explained for the segment 831. The "service charge" symbol key 90 (Figs. 1 and 5), designated by the letters "SC," and the "non-count" symbol key, designated by the letters "NC," each has therein a stud adapted to cooperate with corresponding projections 849 and 850 formed on the peripheral surface of the segment 846.

The manner in which the segment 846 is linked to the shaft 784 causes said segment to be operated in unison with the segment 831 when the key lock shaft 69 (Fig. 8) is rocked clockwise by the initiation of machine operation. Depression of either the "service charge" symbol key 90 or the "non-count" symbol key 90 moves the stud carried by the depressed key into the path of the corresponding projection 849 or 850 to block clockwise movement of the segments 846 and 831 to prevent operation of the automatic check-counting mechanism, even if the Check key 82 is depressed. The depression of either of these keys likewise causes an identifying character to be printed opposite the corresponding amount on the statement sheet.

Inasmuch as the Check key 82 (Fig. 1) is used in conjunction with the Sub-Total key 76 and the Clear key 77 either to read or to clear the check totalizer on the No. 2 line, it is necessary to provide means under control of the Sub-Total and the Total keys 76 and 77 and the other total keys to prevent operation of the automatic check-counting mechanism at this time.

Referring now to Figs. 1, 5, and 7, a total row control bar 857 is mounted for circular shifting movement by means of slots therein in cooperation with two studs 858 in the total key framework. The bar 857 has a plurality of camming projections 851, which cooperate respectively with studs in each of the control keys 74 to 78 inclusive and the Balance Forward key 88. The lower end of the bar 857 has a slot, which embraces a stud 852 in a latch 853 free on the rod 101 and having an L-shaped slot 854 in a right-hand extension thereof, through which extends a stud 855 in a crank 856 secured on the shaft 784.

Depression of one of the control keys 74 to 78 inclusive or of the Balance Forward key 88 causes the stud therein, in cooperation with the corresponding camming projection 851, to shift the control bar 857 downwardly to rock the latch 853 counter-clockwise to cause the vertical branch of the L-shaped slot 854 to latch over the stud 855 to secure the crank 856 and the shaft 784 against movement to prevent the automatic check-counting mechanism from functioning. When none of the total control keys is depressed, the horizontal branch of the L-shaped slot 854

is opposite the stud 855, as shown in Fig. 7, and permits unobstructed operation of the shaft 784.

Depression of any one of the units check-counting keys 72 (Fig. 4) causes the stud 818 therein, in cooperation with the camming surface 817 on the control bar 815, to rock the lever 811 clockwise, causing the camming surface thereon, through the stud 798 and the finger 796, to rock the lever 795 counter-clockwise to move the vertical branch of the L-shaped slot 821 in said arm over the stud 822 to block movement of the shaft 784, thereby disabling the automatic check-counting mechanism when a units check-counting key 72 is depressed. Similar mechanism, illustrated in Fig. 6 and explained hereinbefore, is provided for the tens check-counting keys 52, and, when any one of these keys is depressed, the arm 804 therefor is rocked counter-clockwise to move the vertical branch of the L-shaped slot 825 over the stud 826 to lock the shaft 784 against movement, thereby disabling the automatic check-counting mechanism when any one of the tens check-counting keys 52 is depressed, even though the Check key 82 (Fig. 1) is used to initiate machine operation.

An example of the necessity of the latching mechanism described above to prevent operation of the shaft 784 when the check-counting keys 72 and 52 are depressed is the setting up of the number "20" on the check-counting keys. In this case, the "2" key in the tens check-counting row is depressed, and no key is depressed in the units rows. Inasmuch as the Check key 82 is used to initiate an operation of this type, the "1" surface 782 of the zero stop 783 for the units bank would in this case be moved into the path of the stud 780 to cause "1" to be automatically added in the units order of the check-counting wheels were it not for the latch mechanism shown in Fig. 6, which latches the shaft 784 against movement, so that the "0" surface 781 of the zero stop pawl 783 will remain in the path of the stud 780 to position the differential for the units check-counting bank at zero.

The latching of the slots 821 and 825 over the studs 822 and 826 upon operation of the throwout shaft 204 and the rod 802 in sub-total or total-printing operations is purely incidental, due to the construction of the mechanism, and performs no essential function, as depression of any one of the total control keys 74 to 78 inclusive or the Balance Forward key 88 has already latched the shaft 784 against movement before the shaft 204 receives sufficient clockwise movement to latch said shaft 784 against movement.

While the form of mechanism herein shown and described is admirably adapted to fulfill the objects primarily stated, it is to be understood that it is not intended to confine the invention to the one form or embodiment disclosed herein, for it is susceptible of embodiment in various forms all coming within the scope of the claims which follow.

What is claimed is:

1. In a machine of the class described, the combination of a totalizer line; a set of add-subtract totalizer elements on the line consisting of pairs of reversely rotatable gears spaced apart on said line, a set of item-counting elements on the line consisting of pairs of rotatable gears, each pair connected to rotate together; actuators for the totalizer elements; manipulative devices to control the movement of said actuators; means to condition the set of add-subtract totalizer elements for a subtract operation by shifting the

said line to move one of each pair of said reversely rotatable gears out of alignment with the actuators and to move the other one of each pair of said reversely rotatable gears into alignment with the actuators; actuators for the counting elements, one gear of each pair of counting gears normally aligned with the counting element actuators, and the other gear of each pair of counting gears movable into alignment with the counting element actuators when the totalizer line is shifted to condition the set of add-subtract totalizer elements for subtract operations, whereby items can be subtracted from the add and subtract totalizer and items can be added into the item counting elements during the same machine operation; means normally effective to arrest the actuators for the counting elements in zero, the arresting means for the units order also adapted to arrest the actuator for the units counting element in "1" position; and means rendered effective by the conditioning means to render the arresting means for the actuator for the units counting element ineffective to arrest said actuator in zero, but effective to arrest said actuator in "1" position to cause "1" to be added in said counting element.

2. In a machine of the class described, the combination of a totalizer line; a balance totalizer on the line consisting of pairs of reversely rotatable gears spaced apart on said line for computing debit and/or credit items; an item-counting device on the line consisting of pairs of rotatable gears, each pair connected to rotate together; actuators for the item-counting device; means normally effective to stop the actuators in zero position, the stopping means for the units actuator also adapted to stop said actuator in "1" position; means to condition the balance totalizer for a subtract operation by shifting the said line to move one of each pair of said reversely rotatable gears out of alignment with the actuators and to move the other one of each pair of said reversely rotatable gears into alignment with the actuators, one gear of each pair of counting gears normally aligned with the counting element actuators, and the other gear of each pair of counting gears movable into alignment with the counting element actuators when the totalizer line is shifted to condition the set of add-subtract totalizer elements for subtract operations, whereby items can be subtracted from the add and subtract totalizer and items can be added into the item counting elements during the same machine operation; a manipulative means to initiate said subtract operation to subtract a certain class of items from said balance totalizer; and means controlled by the manipulative means to render the stop means for the units actuator ineffective to stop said actuator in zero position and effective to stop said actuator in "1" position to automatically count "1" for each item in said certain class.

3. In a machine of the class described, the combination of an item-counting device including units and tens orders of counting elements; actuators for each order of item-counting elements; means to position the actuator for the

units element in either zero or "1" position, said means normally effective to position said actuator in zero position; means to position the actuator for the tens element in zero position; means including a member effective upon machine operation to control the above positioning means; a control key to initiate machine operation to enter a certain class of items, said control key also adapted to control the member to cause the positioning means for the units actuator to be moved to one position to enter 1 in the counting element for each item entered in said certain class; other control keys for entering items in another class, said other keys adapted to control the member to cause the positioning means to position the actuators at zero; and a correction key to cancel items erroneously entered in said certain class; said correction key permitting the member to move the positioning means for both actuators to ineffective position to in turn permit said actuators to travel full distance to 9 position, to add 99 to the counting elements, which in effect is equivalent to subtracting 1 from said element for each item cancelled.

4. In a business machine adapted to perform adding, subtracting, and total-printing operations, said machine having printing means, a totalizer line, and a balance totalizer on the line for the recording and registering of positive and/or negative items, the combination of an item-counting element on the totalizer line; depressible item-counting keys; a differential device to transfer the number of items from the keys to the item-counting element and the printing means in adding and subtracting operations and to transfer the total number of items from the item-counting element to the printing means in total-printing operations; a stop member for the differential device; an actuator for the stop member; depressible item-entering keys effective when depressed to prevent movement of the actuator to cause the stop member to arrest the differential device in zero position; a key for entering a particular item, said key effective when depressed to permit partial movement of the actuator to cause the stop member to arrest the differential device in "1" position to count the particular items; a correction key for the particular item, said key effective when depressed to permit full movement of the actuator to move the stop member out of cooperative relationship with the differential device to permit said device to travel to "9" position to subtract one from the counting element by adding the complement 9 therein; means operated by depression of any one of the item-counting keys to move the stop member out of cooperative relationship with the differential device to cause said device to be positioned by the depressed item-counting key; and means effective in total-printing operations to cause the stop member to be moved out of cooperative relationship with the differential device to permit said device and the printing means to be positioned by the item-counting element.

ARTHUR R. COLLEY.
